UNITED STATES PATENT OFFICE

WARREN M. OSBORN, OF CHICAGO, ILLINOIS

RAIL SILENCING TIE PLATE

Application filed April 11, 1931. Serial No. 529,365.

My invention relates to tie plates for railroad rails, and its object is to provide a new and improved device of this character which when used in the ordinary manner of tie-
5 plates between the rail and ties provides a resilient seat for the rail-base and acts as a sound-deadening or silencing device, and in which the metal plate does not carry or dis-
tribute the load as is usually done by tie-
10 plates. Other advantages will be apparent
from the disclosure.

In the accompanying drawings, Fig. 1 is a top plan view showing a tie-plate constructed in accordance with my invention, the
15 associated pad being omitted for convenience of showing the plate itself; Fig. 2 is an end view of the plate of Fig. 1; Fig. 3 is a sectional view taken on the line 3—3 of Fig. 1 looking in the direction of the arrows;
20 Fig. 4 is a detail sectional view taken on the line 4—4 in Fig. 1, and Fig. 5 is a view in cross-section showing the plate and its resili-
ent pad assembled in place between a rail-
base and a tie.

25 In the drawings the reference letter A designates the base of a rail, B its web and C one of the cross-ties on which the device is supported.

The tie-plate body consists of a flat metal-
30 lic strip 10 provided near each side with a flange 11 which preferably extends the full length of the plate and provides a shoulder for the corresponding edge of the rail-base. The shoulders may be integral for their en-
35 tire length or they may be in sections as shown, and spike-holes 12 are formed outside the shoulders to receive suitable spikes (not shown) to fasten the plate to the tie. Adjacent each spike-hole the plate and its shoulders may be beveled as shown at 14 to form seats for the spike-heads; in the present exemplification the seats are shown as circular to accommodate round-headed spikes.

40 The shoulders are of sufficient height to ex-
tend above the edges of the rail-base, and the distance between the shoulders is slightly greater than the width of the rail-base.

45 When the rail is assembled on the plate it
50 is held in place and guided by the shoul-

ders, and the plate need not be disturbed in making rail renewals or replacements.

The body of the plate is made in skeleton form as shown in Fig. 1 to provide a cen-
55 tral opening or space 15 for suitable resilient pads 16 which are seated in these spaces, as shown for example in Fig. 5. The pads sub-
stantially fill these spaces, though slight clearance between their edges and the walls
of the plate may be left if desired, and the
60 pads are thicker than the adjacent walls of
the plate so that in their normal relation the rail-base is carried by the pads without con-
tacting with the end pieces 17 of the plates.
The pads have a width slightly greater than
65 that of the rail-base, and as they are thicker
than the plates all wear comes on the pads;
when they become worn or lose some of their
resiliency they can be removed and renewed
70 by merely lifting the rail without disturbing
the plate or tie. The pads preferably are
75 slightly wider than the rail-base, and are of
such length that the ends 17 of the plate have
sufficient metal to give them proper strength
when placed under tension by the rails under
traffic. The plate itself does not carry or dis-
80 tribute the load as ordinary tie plates do, it
does not get worn or bent under the action
of the rails in traffic, and does not wear the
tie, as the pads carry the load through the
85 plate opening directly to the ties and hold
the rails out of contact with the plates, and
are in turn held in proper position under the
rails by the walls of the openings 15. These
tie plates when placed on the ties, whether
90 plain or creosoted, will outlast the ties. The
rail may be fastened to the plate by any suit-
able means. The pads protect the tie from
the wear which is caused by plates upon which
the rails rest, thus prolonging the life of the
95 ties and obviating the necessity of their fre-
quent replacement.

I claim:

1. A metallic rail plate having a body pro-
vided with opposite shoulders and an inter-
mediate opening through its body, and a re-
silient pad shaped to fit into said opening.

2. A metallic rail plate having integral
side and end portions forming an intermedi-
ate opening, shoulders on said side portions

forming a space for the base of an associated rail, and a resilient pad shaped to fit into said opening and thicker than the walls of said opening.

3. A metallic rail plate having a skeleton body composed of opposite sides and opposite ends enclosing an opening through the intermediate portion of the plate wider than the flange of an associated rail, shoulders on the sides higher than said rail-flange, and a resilient pad shaped to fit into said opening and thicker than the adjacent walls thereof and wider than said rail-flange.

10 In testimony whereof I hereto affix my
15 signature.

WARREN M. OSBORN.
